LIGHTING FIXTURE

Howard Rowland, Chicago, Ill., assignor to Electrical Testing Laboratories, New York, N. Y., a corporation of New York

Application February 4, 1941, Serial No. 377,291

4 Claims. (Cl. 240—78)

The present invention relates to lighting fixtures and particularly to improvements in fixtures of the type which employs a bi-post lamp and bi-post socket.

Where bi-post lamps and sockets are used in the usual pendent position there is a tendency for the socket and adjacent parts to heat excessively. This arises from the high currents which must be handled with consequent high resistance losses in conducting parts and contacts, and from the heating of the socket by the convection stream rising from the small diameter lamp itself. Tests of 1,000 watt equipment have indicated that with the lamp and socket alone in open air at ordinary room temperatures there may be temperatures of the order of 420° F. to 480° F. at the prong clips with from 340° F. to 370° F. at the wire binding screws.

As it is necessary for reasons of appearance to conceal the socket and wiring some form of socket cover is usually employed. The usual form of enclosing husk or socket cover used with screw base sockets and lamps was adopted by numerous manufacturers and experience has proven that such arrangements were generally unsatisfactory. Socket temperatures rose considerably—in typical cases prong clip and binding wire screw temperatures in excess of 100° F. higher than open air conditions would be found, and where the same lamp and socket were used. Operation at these excessively high temperatures causes the contacts to deteriorate and is likely to bring about an early failure of the socket. The higher prong clip temperature is of course transmitted to the wire at the point of contact making it necessary to use more expensive wire than would otherwise be required.

The present invention contemplates improvements in the construction of lighting fixtures of the type employing bi-post sockets and lamps whereby the socket parts may be kept at materially lower temperatures than with the common forms of construction.

The accompanying drawing shows, for purposes of illustrating the present invention, several embodiments in which the invention may take form, it being understood that the drawing is illustrative of the invention rather than limiting the same.

In this drawing:

Figure 1 is a side elevational view of a lighting fixture embodying the present invention;

Figure 2 is a vertical sectional view through the same at an enlarged scale;

Figures 3 and 3a are fragmentary sectional views at a more enlarged scale;

Figures 4 and 5 are diagrammatic sectional views of modified forms of construction; and

Figure 6 illustrates a typical prior art construction used for comparative tests.

In the customary or known form of construction of Figure 6 the usual bi-post socket S with yoke Y and carrying a bi-post lamp L are secured in the usual way to a hanger H. The socket S is received in a metal socket cover or husk C of somewhat larger diameter than the socket and extending slightly below the socket. It may have ventilation holes at the top. Sheet metal louver rings R₁ and R₂ are also provided to shield the upper part of the lamp L. When such equipment with 1,000 watt lamp and the usual open topped indirect lighting bowl was operated the average clip contact rise above room temperature was 490° F. This temperature is higher than the contacts should be expected to carry.

The construction shown in Figures 1, 2 and 3 illustrates an arrangement of parts in which tests showed a reduction of temperature rise of the order of 160° F. bringing the temperature of the clip contacts in the concealed and housed socket below what they would have been had the socket and lamp been operated in open air.

The socket S, lamp L and hanger H may be the same as before. The lamp has the usual posts 10—10 adapted to pass through and interlock with the usual supporting springs 11 and enter the usual clip contacts 12. The clip contacts are carried on terminal straps 13 and binding screws 14 connect these straps to wires 15.

The socket S is received in a tube 20 which preferably fits very closely about the socket so that heat is readily conducted away from the socket. The lower edge of the tube is even with the lower edge of the socket and the tube extends above the socket. In order to keep dust off the top of the socket the tube is closed at the top and a convenient form of construction is to provide the tube with a conical top 21 adapted to engage a flange 22a of a tube 22 disposed about the hanger H. The tube 20 hangs from this support.

The lower end of tube 20 is flanged outwardly as indicated at 23 and this flange supports an upwardly and outwardly flaring air deflector 24. This may have an angle of about 30° with the vertical and a diameter about twice that of the socket. The flange 23 is notched at 23' and a number of straps 25 extend downwardly along-side the lamp. These straps support two louver

or baffle rings 26 and 27. These rings extend from close to the lamp surface upwardly and outwardly so as to deflect the convection stream away from the fixture axis. These baffle rings are cones with a common apex at the light center L. C. They therefore present the minimum obstruction to the passage of radiant heat and direct light from the source, at the same time screening the top of the lamp. The lower baffle ring is notched at 28 to receive rods 29 adapted to support a bowl 30.

In Figure 3a the socket is shown as having a lower clamping ring 16 of larger diameter than the standard clamping ring 17 of Figure 3. It assists in conducting heat away from the top of the lamp.

Figure 4 shows diagrammatically an arrangement in which the air deflector 31 and louver rings 32 and 33 are the same as the corresponding parts of Figures 1 and 2. The tube 34 which receives the socket S is longer than the cylindrical part of tube 20. Here the top of the tube is shown as open. With this arrangement about the same temperatures are observed.

Closing the top of 26 or of 34 or of 31 and 34 has been found to bring about higher temperatures than with these parts open, but temperatures substantially below those produced in the customary construction.

Figure 5 shows diagrammatically an arrangement in which the socket is received in a long cylindrical tube 35 with air deflector 36 similar to air deflector 24. The baffle or louver rings 37 and 38 are arranged like R₁ and R₂, Figure 6. The temperature conditions in this arrangement are slightly higher than those in the arrangement of Figure 2, and there is some loss and redistribution of light.

In use the improved fixtures shown herein present an attractive appearance as the louvers and air deflector have pleasing lines. The light output is not sensibly affected, but the distribution is slightly altered owing to reflection of the zone of direct light which falls on the air deflector.

It is apparent that, within the scope of the invention, modifications and different arrangements may be made other than is herein disclosed, and the present disclosure is illustrative merely, the invention comprehending all variations thereof.

What is claimed is:

1. In a lighting fixture, a pendent bi-post lamp socket, a bi-post lamp therein, a socket enclosing tube fitted closely about the socket extending above the socket and having its lower edge substantially even with the lower edge of the socket, a conical air deflector having its lower end substantially even with the bottom of the socket and in close contact with the tube, the deflector being of substantial height and of substantially wider outer diameter than the tube so that air heated by the lamp is kept away from the tube and socket, and upwardly and outwardly diverging conical baffle rings below the air deflector and above the light center of the lamp, the rings acting to direct heated air intercepted thereby outwardly and keep it away from the conical air deflector to reduce the heating of the socket contacts and lamp terminals.
2. A lighting fixture such as claimed in claim 1, wherein the baffle rings converge toward the light center of the lamp so as to intercept the minimum of direct light and radiant heat.
3. A lighting fixture comprising a pendent support, a bi-post lamp socket secured to the lower end of the support, a bi-post lamp in the socket, a socket enclosing tube fitted closely about the socket, means for supporting the tube from the pendent support with its lower end substantially even with the bottom of the socket, an upwardly and outwardly flaring conical air deflector extending to and carried by the lower end of the tube, said deflector having its lower end substantially even with the bottom of the socket and in close contact with the tube, straps extending downwardly from the tube and about the upper part of the lamp, upwardly and outwardly flaring conical baffle rings secured to the straps, the rings and deflector acting to direct heated air intercepted thereby outwardly and keep it away from the socket enclosing tube to reduce the heating of the socket contacts and lamp terminals, and an upwardly opening lamp receiving bowl supported from the straps with its upper edge substantially level with the lowermost ring.
4. A lighting fixture such as claimed in claim 3, wherein the socket is carried on a yoke, the upper end of the tube converges inwardly and the tube supporting means includes a sleeve about the pendent support and extending from the yoke to the narrowed end of the tube.

HOWARD ROWLAND.
